Primary Examiner — Cynthia Underwood

(57) **CLAIM**

The ornamental design for a serving dish, as shown and described.

DESCRIPTION

FIG. 1 is a top, side and front perspective view of the first embodiment of a serving dish showing my new design;

FIG. 2 is a front elevation view, the rear elevation being a mirror image thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a cross-sectional view taken along line 7-7 of FIG. 5;

FIG. 8 is a cross-sectional view taken along line 8-8 of FIG. 5;

FIG. 9 is a top, side and front perspective view of the second embodiment of a serving dish showing my new design;

FIG. 10 is a front elevation view, the rear elevation being a mirror image thereof;

FIG. 11 is a right side elevation view thereof;

FIG. 12 is a left side elevation view thereof;

FIG. 13 is a top plan view thereof;

FIG. 14 is a bottom plan view thereof;

FIG. 15 is a cross-sectional view taken along line 15-15 of FIG. 13; and,

FIG. 16 is a cross-sectional view taken along line 16-16 of FIG. 13.
